(57) **CLAIM**

The ornamental design for a combined beverage cooler and dispenser as shown and described.

DESCRIPTION

FIG. 1 is a top perspective view of a beverage cooler and dispenser with a cart attached showing our new design;

FIG. 2 is bottom perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and

FIG. 8 is a bottom view thereof.

FIG. 9 is a bottom perspective view of the cart for the beverage cooler and dispenser showing our new design;

FIG. 10 is a top perspective view thereof;

FIG. 11 is a rear perspective view thereof;

FIG. 12 is a top view thereof;

FIG. 13 is a front view thereof;

FIG. 14 is a side view thereof, with the opposite side being identical; and

FIG. 15 is a bottom view thereof.

FIG. 16 is a top perspective view of a beverage cooler and dispenser showing our new design;

FIG. 17 is a bottom perspective view thereof;

FIG. 18 is a front view thereof;

FIG. 19 is a rear view thereof;

FIG. 20 is a side view thereof;

FIG. 21 is an opposite side view thereof;

FIG. 22 is a top view thereof; and,

FIG. 23 is a bottom view thereof.

UNITED STATES PATENT AND TRADEMARK OFFICE
CERTIFICATE OF CORRECTION

PATENT NO. : D1,069,514 S
APPLICATION NO. : 29/855260
DATED : April 8, 2025
INVENTOR(S) : Daniel Harden et al.

Page 1 of 1

It is certified that error appears in the above-identified patent and that said Letters Patent is hereby corrected as shown below:

On the Title Page

Right Column, item (57), Description, Lines 17-18, "FIG. 1 is a top perspective view of a beverage cooler and dispenser with a cart attached showing our new design;" should read --FIG. 1 is a top perspective view of a first embodiment of a combined beverage cooler and dispenser, showing our new design;--

Right Column, item (57), Description, Lines 26-27, "FIG. 9 is a bottom perspective view of the cart for the beverage cooler and dispenser showing our new design;" should read --FIG. 9 is a bottom perspective view of a second embodiment of a combined beverage cooler and dispenser, shown without the cooler;--

Right Column, item (57), Description, Lines 35-36, "FIG. 16 is a top perspective view of a beverage cooler and dispenser showing our new design;" should read --FIG. 16 is a top perspective view of a third embodiment of a combined beverage cooler and dispenser, shown without the cart;--

On page 2, left Column, prior to the text on Line 1, please insert --The broken lines in the figures illustrate the portions of the combined beverage cooler and dispenser that form no part of the claimed design.--

Signed and Sealed this
Seventeenth Day of June, 2025

Coke Morgan Stewart
Acting Director of the United States Patent and Trademark Office
